UNITED STATES PATENT OFFICE.

JUSTUS R. KINNEY, OF ALLSTON, MASSACHUSETTS, ASSIGNOR TO THE KINNEY MANUFACTURING COMPANY, OF BOSTON, MASSACHUSETTS, A CORPORATION OF MASSACHUSETTS.

VALVE.

1,234,181.

Specification of Letters Patent. Patented July 24, 1917.

Original application filed June 2, 1915, Serial No. 32,009. Divided and this application filed March 10, 1917. Serial No. 155,100.

To all whom it may concern:

Be it known that I, JUSTUS R. KINNEY, a citizen of the United States of America, and a resident of Allston, in the county of 5 Suffolk and Commonwealth of Massachusetts, have invented certain new and useful Improvements in Valves, of which the following is a specification.

This invention relates to apparatus for 10 applying liquids to roads and valves adapted to be used in connection therewith, and has for its object the production of a device of this class by which air may be admitted to the various pipes in the spraying system 15 so that all oil may be removed therefrom by means of the pump forming a part of said system.

The invention further consists in certain 20 novel features of construction and arrangement of parts which will be fully understood by reference to the description of the drawings and to the claims hereinafter given.

For the purpose of illustrating the invention, one preferred form thereof is illustrated in the drawings, this form having been found to give satisfactory and reliable results, although it is to be understood that the various instrumentalities of which the 30 invention consists can be variously arranged and organized, and that the invention is not limited to the precise arrangement and organization of these instrumentalities as herein shown and described.

35 Of the drawings:

Figure 1 represents an elevation of the tank of a road oiler to which is applied a valve embodying the principles of the present invention.

40 Fig. 2 represents a vertical section of the discharge pipe from the tank with the valve operating mechanism therefor, the valve being shown open.

Fig. 3 represents a similar section with 45 the valve closed and the vent to the discharge pipe open.

Fig. 4 represents a plan view of the rear end of the chassis of said road oiler with the various devices thereon for controlling the 50 flow of the material, and

Fig. 5 represents a side elevation of the same.

Similar characters designate like parts throughout the several figures of the drawings.

55

In the drawings, 10 is a tank provided at the top with the filling dome 11 through which the tank may be filled from any suitable source of supply located above said tank. The tank 10 is supported on cradles 60 12 made of flat metal bars bent to form a seat for the tank with inwardly extending feet which are secured to a demountable frame 13.

The demountable frame 13 is supported 65 on the chassis or frame 15 of a truck having the usual supporting wheels and an engine mounted thereon by which the rear wheels may be driven in any well-known manner.

Mounted on the frame 13 is the revoluble 70 shaft 29 of a rotary pump 30. Means is provided whereby the pump 30 may be operated by the engine when the vehicle is moving over the road or may be thrown out of commission as desired. It is obvious, more- 75 over, that when the vehicle is at rest and the engine is in operation, while the transmission mechanism is thrown out of commission in the usual manner, the pump 30 may be placed in commission at will and be driven 80 by said engine, all as fully shown and described in the application, Ser. No. 32,009 filed by me June 2, 1915, of which application this application is a division.

The inlet side of the pump 30 is connected 85 by means of a pipe 42 to a suction strainer 43 of any well-known construction, and a discharge strainer 44 of any desired type is connected to the discharge outlet of said pump by means of the pipe 45, said strainer 90 44 communicating with the flushing and sprinkling systems, all as fully described in the application No. 32,009, above referred to.

The pipes 42-45 are connected by a bypass pipe 46 having a relief valve 47 there- 95 in. The strainer 44 is connected by a pipe 48 with a three-way cock 49, one branch of which is connected to a transverse pipe 50, the opposite ends of which are connected with the rearwardly extending pipes 51, 100 each of which has a valve 84 to control the discharge of material therethrough.

The pipe 48 is connected to the member 53 secured to the bottom of the tank 10 by

a discharge pipe 54, said member 53 having a valve seat 55 with which coacts a closing valve 56 shown in Figs. 1, 2, and 3 of the drawings.

5 The valve 56 is mounted upon the lower end of a tubular valve stem 57 extending upwardly through the tank 10. The lower end of the stem 57 has a bearing at 58 and mounted on its upper end is a revoluble 10 sleeve 59 prevented from endwise movement thereon.

The sleeve is threaded to a fixed nut 60 in a flanged member 60* secured to the upper side of the tank 10 and may be rotated 15 therein by the handle 61 to move the valve 56 to and from its seat 55 to regulate the discharge of material from said tank.

The tubular stem 57 extends through the hub of the handle 61 and has at its upper 20 end a pet cock 62 adapted to close the passage through said stem 57 when the valve 56 is open. When the valve 56 is closed the pet cock is moved into the position shown in Fig. 3, thereby permitting the air to pass 25 through the stem 57 into the discharge pipe 54.

On either side of and parallel to the stem 57 are distance rods 63 extending across the tank 10 and serving to strengthen the 30 same, the ends of said rods 63 being positioned in the housing 58* and the flanged member 60*.

The pipe 45 also has leading therefrom a discharge pipe 64 having a cutoff valve 65 35 therein. The end of the pipe 64 is threaded to receive a hose through which the contents of the tank may be discharged when it is desired to empty the tank without sending the material through the sprinkler systems. From the bottom of the strainer 44 40 is another discharge nozzle 66 through which the material may be drained from the strainer. The discharge nozzle is normally closed by the valve 67.

45 The tank 10 is provided at its front end with a chamber 110 from which extend to and through a head 111 near the rear thereof a plurality of heating pipes 112 through which hot air is adapted to pass from the 50 heater chamber 113 situated at the rear end of the tank 10.

From the top of the chamber 110 extends an outlet pipe 120 to carry off the heat therein.

55 The suction strainer 43 has secured to its outer wall a valve 121 through which the tank 10 is adapted to be filled with liquid, the valves 56 and 65 at this time being closed and the liquid passing through the 60 strainer 43 and pipe 42 to the pump 30, from which it is forced through the pipe 45 to a valve 122 which is open, and then through the pipe 123 into the top of the tank 10, the valve 45* having been turned 65 to communicate with said pipe 123.

The tank having been filled, the inlet valve 121 is closed and the valve 56 opened, and the valve 45* is then turned so that the liquid may flow from said tank through the strainer 43 into the pipe 42 to the pump 70 from which it is forced through the pipe 45 to and through the valve 49 into the pipes 50-51 to the valves 84 which if open will permit the discharge of the liquid through the oil spray pipes 73.

75 When the oil spray system is in use the valve 65 is closed but if it is desired to empty the tank this valve 65 is opened and the valves 84 and 122 closed, the valve 45* being turned to communicate with pipe 64. The liquid will then be discharged through the pipe 64. The end of this pipe is threaded and a hose may be attached thereto so that if the tank is filled with water a stream may be forced therethrough for the purpose of putting out fires. While the pump 30 is in operation, if any of the cutoff valves are closed temporarily the liquid discharged from the pump 30 will pass through the bypass pipe 46 to the inlet side of the pump, the relief valve 47 permitting this operation when a predetermined pressure has been reached.

On each side of the tank 10 is a reservoir 126 adapted to contain kerosene or some similar oil. From each reservoir 126 extends a pipe 127 having a valve 128 therein and the two pipes 127 both connect with the pipe 129 communicating with the discharge pipe 54 immediately below the valve 56.

95 Each of the reservoirs 126 is connected by pipes 139 to an air pump 140 operated by a handle 141. By means of this pump 140 the oil in the reservoirs 126 is maintained at a pressure of 40 lbs.

100 The tank 10 may either be filled by pump suction, or it may be filled by any suitable gravity supply by removing the manhole cover 140 and filling through the opening by any suitable conducting hose or pipe.

105 Whenever it is necessary to stop the distribution of the oil for any length of time before the tank is entirely emptied, the valve 56 is closed and the vent cock 62 is opened. The valves 84 are then opened and the pump 30 is run until the piping system is entirely free from material.

110 The circulating valve 122 is then closed and the kerosene oil valve 142 is opened, allowing a jet of kerosene oil to enter the pump and piping system, and the pump 30 is kept running until the kerosene oil forced through the piping system has thoroughly cleared the same.

115 The drain cocks 67 are then opened to permit the draining of the strainer casings 43 and 44.

120 One of the great advantages of the present invention is that means are provided whereby the entire pipe system may be 130

thoroughly cleared of oil and the tank may be filled with water and the apparatus then used for watering the streets.

It is believed that the operation and many advantages of this invention will be fully understood from the foregoing description.

Having thus described my invention, I claim:

1. In a device of the class described, the combination of a tank provided with an outlet therefrom; a pipe from said outlet; a pump connected with said pipe; a valve for said outlet; a tubular member the upper end of which extends through the tank casing and the lower end of which extends through the said valve and opens into said pipe; means coöperating with said tubular member for raising and lowering said valve; and a pet cock on the outer end of said tubular member.

2. In a device of the class described, the combination of a tank provided with an outlet therefrom; a valve for said outlet; a tubular member the upper end of which extends through said tank casing and the lower end of which extends through the said valve; means coöperating with said tubular member for raising and lowering said valve; and a pet cock on the outer end of said tubular member.

3. In a device of the class described, the combination of a tank provided with an outlet therefrom; a valve for said outlet; a tubular member the upper end of which extends through said tank casing and the lower end of which extends through the said valve; a threaded member inclosing the

upper end of said tubular member and movable endwise therewith; a nut therefor secured to said tank; means for rotating said threaded member; and a pet cock on the outer end of said tubular member.

4. In a device of the class described, the combination of a tank; a housing secured to said tank having an outlet therefrom; a valve in said housing for controlling said outlet; a tubular member extending through said valve at one end and through the top of the tank at the other end; a pet cock in the outer end of said tubular member; and means coacting with the upper end of said tubular member for raising and lowering said valve.

5. In a device of the class described, the combination of a tank; a housing secured to said tank having an outlet therefrom; a valve in said housing for controlling said outlet; a tubular member extending through said valve at one end and through the top of the tank at the other end; a pet cock in the outer end of said tubular member; an annular flanged member secured to the upper end of said tank; a nut secured therein; a sleeve surrounding said tubular member between shoulders thereon and threaded to said nut; means for turning said sleeve; and distance rods between said housing and flanged member.

Signed by me at 4 Post Office Sq., Boston, Mass., this 9th day of March, 1917.

JUSTUS R. KINNEY.
